UNITED STATES PATENT OFFICE

1,971,332

FAN PROTECTOR

Emma K. Cook, St. Louis, Mo.

Application July 18, 1932, Serial No. 623,169

2 Claims. (Cl. 230—275)

This invention relates to fan protectors and more particularly to a further development and improvement in the fan protector described by me in patents granted to me on the 25th day of 5 March, 1930, #1,751,793, and also the 9th day of June, 1931, #1,809,583.

The object of the present invention is to provide a more durable and convenient structure that can be manufactured at a lower cost and 10 may be more easily attached to and detached from fans already in the hands of users.

Other objects and advantages of this invention will be disclosed in the specification, claims and drawing, in which:

15 Fig. 1 is a side elevation of a fan equipped with my protector.

Fig. 2 is a front elevation of a fan equipped with my protector.

Fig. 3 is a view of the rear portion of my 20 protector, showing the manner of locking the protector on the frame of a fan.

Fig. 4 is a view of the rear portion of my guard in expanded position.

Fig. 5 is an enlarged detail view of the locking 25 mechanism.

Fig. 6 is an enlarged detail view of a portion of the rear portion of my protector locked in position.

Fig. 7 is a section along the line 7—7 in Fig. 5.

30 Fig. 8 is a view of the locking wedge.

The body of the protector is preferably made of wire mesh cloth 1 or other suitably foraminated material bound about its peripheral edges by metal stripping 2 folded over the edge of 35 the wire mesh, as best shown in Fig. 6 at 3, wherein the outer fold 4 is folded against the fold 5 and the third fold 6 is clamped down tightly against the wire mesh 1.

The outer fold 4 extends outwardly from the 40 rear edge 7 of the main body portion of the protector and is bent so as to form a groove about the periphery of the protector for the purpose of receiving the flexible rear portion 8, which, by means of the opening 9 is capable of being contracted in order to fit into the groove 7 and then expanded by means of a wedge-shaped locking piece 10 which is forced radially inward in the guideways formed under the folds 11 formed by folding the metal over the edges of 50 the wire mesh 1, as best shown in Figs. 5 and 7.

The front and sides of the protector are preferably rigidly joined together by means of metal stripping 13, and the protector may then be placed over the front of a fan, the rear portion 55 of the protector 8 then contracted as above

explained and fitted into the groove 7, and then expanded by inserting the wedge piece 10, thus holding it firmly in position and at the same time making it easy to remove the protector for cleaning the fan, etc.

It is obvious that under this method of construction a neat and attractive protector is provided.

Having fully described my invention, what I claim as new and useful and desire to protect by 65 Letters Patent is:—

1. A fan protector of the class described, comprising a front of wire mesh cloth cut to size having its marginal edges bound by thin sheet metal stripping clamped about said marginal edges 70 adapted to interlock with a mating member clamped about the marginal edges of the side walls of said fan protector, side walls composed of wire mesh cloth formed into a cylindrical member having its front marginal edges bound about with thin sheet metal stripping adapted to interlock with said front member and having its rear marginal edges bound with metal stripping, said metal binding extending rearwardly and projecting beyond the wire mesh cloth thereby to 75 provide a groove peripherally disposed about the marginal edge of said projecting member adapted to receive the marginal edge of a contractable and expandable member, an expandable and contractable rear member adapted to be contracted and expanded into and out of said groove and wedge means for holding said rear member in 80 said groove.

2. A fan protector of the kind described, comprising a front member of wire mesh; a cylindrical side wall member of wire mesh and having its front peripheral edge bound with a sheet metal stripping enclosing and binding the peripheral edge of said front member to interlock the two in fixed relation; a metal binding enclosing the rear peripheral edge of said side wall member and projecting rearwardly to overhang the wire mesh of the same and provided with an internal peripherally extending groove; a rear closure plate member adapted to be positioned in the plane of said groove and having its ends spaced apart so that said member may be radially expanded or contracted; and a wedge adjustably movable in the space between the ends of said rear plate for expanding the latter firmly into 95 100 105 said groove.

EMMA K. COOK.
